UNITED STATES PATENT OFFICE

CLAIR C. HARPER, OF ROCHESTER, AND EUGENE F. KITENDAUGH, OF ONEIDA, NEW YORK, ASSIGNORS TO ERROR-NO INC., OF ROCHESTER, NEW YORK, A CORPORATION OF NEW YORK

COPYHOLDER

Application filed September 17, 1929. Serial No. 393,304.

Our invention relates to copy holders and especially to that type of copy holder adapted to hold and feed a very wide or long record sheet conveniently to the operator of a calculating, card punching, typewriting or similar machine used in connection with this class of work. The object of our invention is to provide a copy holder of this kind with means for supporting a sheet at the intake side of the machine and to permit it to extend to the rear of the machine to prevent crumpling of the sheet. Another object of our invention is to provide a support for the rear end of the sheet in the copy holder which also serves as a support for the copy holder frame. Another object of our invention is to provide a copy holder with feeding means adapted to positively engage the copy sheet so that all parts of the wide sheet are fed at a uniform speed. Still another object of our invention is to provide adjustable reinforcing means for the feeding devices in a copy holder to maintain a uniform pressure on the sheet throughout its width.

To these and other ends, the invention consists of certain parts and combinations of parts, all of which will be hereinafter described: the novel features being pointed out in the appended claims.

In the drawings:

Fig. 1 is a front elevation of a device constructed according to one embodiment of our invention;

Fig. 2 is a section on the line 2—2, Fig. 1;

Fig. 3 is an elevation of the sheet clamping and feeding devices, the housing being removed to expose the underlying parts, and parts being sectioned away to conserve space;

Fig. 4 is a sectional view on the line 4—4,

Fig. 3, with the housing removed;

Fig. 5 is a similar view on the line 5—5, Fig. 3;

Fig. 6 is an enlarged sectional view of parts shown in Fig. 2; and

Fig. 7 is a side view partially in section of another embodiment of my invention.

The present embodiment of our invention comprises a frame having upwardly and rearwardly extending members 1 to which forwardly and upwardly extending braces 2 are

secured. Secured to and extending between the upright members 1 adjacent their upper ends is a housing or supporting member 3 provided with forwardly extending portions 4 and 4^a in which the paper clamping and feeding devices are mounted. Mounted on a rod or bar 5 and extending between the supporting members 1 near the base of the device is a sheet holding and supporting member 6 extending downwardly and rearwardly therefrom and at its lower rear end extends to a point in the plane on the bottom of the frame. At its rear end the support 6 has formed thereon a flange 7 to retain sheets in the support. At its forward end, the support 6 is curved upwardly and forwardly at 8 for supporting and directing the sheets as they are drawn from the support 6.

Arranged on the front of or integral with the member 3 is a sheet supporting plate or table 9 arranged above the support 6 and on which the sheets or copies are supported as they move to the feeding devices. Movable in said support behind the plate 9 is a shaft 10 on which are mounted a plurality of clamping members or rollers 11 in position to project through openings provided therefor in the plate or table 9. Revolvably mounted in the support 4 in front of the table 9 is a shaft 12 on which are mounted a plurality of feed rollers 13 adapted to engage the rollers 11 or a sheet placed thereon. The shaft 10 is mounted for movement to carry the rollers 11 to and from engagement with the feed rollers 13 and is resiliently held in such engaging position by means of springs 14 which engage the shaft 10. Means are provided for moving the shaft manually to move the rollers 10 out of engagement with the rollers 13 against tension of the springs 14. Said means comprises a shaft 15 journalled in the supporting member and extending parallel with the shaft 10. Adjacent the ends of the shaft 10 the shaft 15 is provided with arms 16 projecting therefrom and adapted to engage the shaft 10. A finger piece 17 is secured on the shaft 15 for rotating the same to move the rollers 11 out of engagement with the rollers 13.

The shaft 12 is on which the rollers 13 are

mounted is angular in cross section, as shown, and engages corresponding openings in the rollers 13 to prevent the rollers from slipping on the shaft. We have provided means 5 for positively engaging the sheet so that both sides of a wide sheet will be fed forwardly at the same speed and creeping of the sheet prevented. To this end, the rollers 11 and 13 are provided with gripping means 10 preferably corrugations, as shown, and the sheet is gripped between the opposing corrugations on the rollers.

When feeding very wide sheets, it sometimes happens that the feeding shaft has a 15 tendency to spring from the work causing uneven pressure to be exerted on the sheet resulting on a feeding of different portions of the sheet at different speeds. To overcome this, we have provided means for reinforcing the angular shaft 12 at one or more points intermediate its ends. To this end, a supporting member 18 extends across the support 3 over the angular shaft 12 and has threaded therein a screw 19 having an abutment 20 swiveled at its inner end and adapted to engage a cylindrical portion 21 on the shaft 12. The outer end of the screw 19 may be provided with a finger piece 22 for adjusting the same.

30 Means are provided for imparting a step-by-step rotary movement to the shaft 12 for the purpose of rotating the roller 13 to feed the sheet forwardly from line to line. To this end, a gear or wheel 25 is mounted on 35 the end of the shaft 12 and engages a wheel 24 revolvably supported on one of the supporting members 4 which in turn meshes with a wheel 23 mounted on a shaft 26 which is revolvably supported in the member 4, 40 and a member 27 on the support 3. At its outer end the shaft 26 is provided with a finger piece by which it may be manually rotated in either direction. To impart step-by-step feeding movements to the rollers 13 45 a friction wheel 28 is mounted on the shaft 26 and a dog or pawl 29 is pivoted on a manually operated lever 30 for limited movement thereon. The lever 30 is mounted to swing on the shaft 26 and has an inwardly extending finger 31 which engages the dog and moves it into clamping engagement with the wheel 28 which thereafter moves with the lever. A spring 32 resiliently maintains the lever in normal retracted position and a pair 55 of stops limits its movement in either direction.

Mounted on the support 18 and curving downwardly and forwardly to a point adjacent the table 9, is a housing member 33 which 60 conceals the intake side of the feeding devices and cooperates with a line guide 34 adjustably mounted on the table 9 and providing a line of vision therebetween. A second housing member 35 for the feeding devices is also 65 mounted on the support 18 and extends up-

wardly and rearwardly therefrom past the table 9 and serves to deflect a sheet moving from the table rearwardly into a tray or pocket 36 provided thereon the rear of the frame. Said pocket is secured to the member 3 and supported on brackets 37 extending upwardly and rearwardly from the frame members 1. The pocket or tray 36 extends downwardly and rearwardly from a point adjacent the discharge side of the machine and is adapted to receive and shut when discharged. At its rear end a flange 38 is provided which serves as a stop for the sheets. It will be noted that the sheet supporting devices 6 and 36 are arranged one above the other on the rear side of the frame with the feeding devices between them and provide means for supporting the opposite ends of a long record or work sheet.

In the embodiment shown in Fig. 7 the sheet feeding means is the same as that shown in the other embodiment. The sheet as it passes from the feeding means travels over a guide 39, the lower portion of which is aligned with the feeding mechanism. From the feeding mechanism, the guide proceeds upwardly, rearwardly and then downwardly in a vertical plane in rear of the supporting members 1.

The sheets pass from the guide to the receiver or tray 40 which is arranged in a rearwardly inclined position in rear of the supporting member 1, its lower forward portion resting on brackets 41 which are carried by the braces 2. Braces 42 connect the sides of the receptacle with the forwardly projecting portions 4 and 4^a in which the feeding mechanism is arranged.

The sheets in dropping from the guide 39 proceed with their upper edges first toward the lowermost part of the receiving tray. In this way the front face of the sheet on the feeding mechanism becomes the rear face of the sheet in the tray. In other words, the position of the sheet is reversed. This is important when a stack of sheets are being successively used in the copy holder and it is desired to maintain the order of the sheets in a stack after passing through the copyholder.

It will be noted that we have provided a simple and inexpensive copy holder designed to conveniently handle large copy sheets. We have provided improved means for positively engaging the sheet to compel all parts to move at the same speed to prevent creeping. A copy holder constructed according to our invention is low so that it may be used on a support such as a desk and the provision of the trays or pockets on the rear of the device facilitates the use of long copy sheets without rolling or folding as heretofore required.

What we claim as our invention and desire to secure by Letters Patent is:

1. In a copyholder, the combination of a frame, sheet feeding means arranged there-

- on, and an auxiliary support for the frame comprising a sheet supporting device secured to the frame and inclined downwardly and rearwardly to a point in the plane of the base of the frame.
- 5 2. In a copy holder, the combination of a frame, sheet feeding means arranged thereon, and a pair of downwardly inclined sheet supporting devices secured to the rear of the frame and arranged on opposite sides of the feeding means, one of said devices being adapted to support the frame.
- 10 3. A copy holder comprising a line guide, a feeding mechanism moving the work past the line guide and arranged above the line guide, and a sheet holding tray having its forward end below the line guide and its rear end situated in rear of the line guide.
- 15 4. A copy holder comprising a line guide, a feeding mechanism moving the work past the line guide and arranged above the line guide, and a sheet holding tray having its forward end below the line guide and its rear end situated in rear of the line guide, said tray extending downwardly and rearwardly from its forward end.
- 20 5. A copy holder comprising an upright plate, a line guide arranged in front of the plate, feeding mechanism for moving the copy over the plate and under the line guide, and a tray having its forward portion arranged below but in spaced relation to the plate and extending rearwardly in rear of the plate.
- 25 6. In a copy holder, the combination with means for feeding sheets one at a time upwardly and rearwardly, of a deflector arranged adjacent the discharge of said feeding means to insure the rearward deflection of the sheet, and a tray supported in rear of said feeding means to receive the sheets discharged by the feeding means.
- 30 7. A copy holder comprising a frame, sheet feeding mechanism on the frame, and a sheet holding tray supported on the frame below the sheet feeding mechanism and extending rearwardly and downwardly, its rear end serving with the frame to support the latter in an upright position.
- 35 8. A copy holder comprising a line guide, a sheet feeding mechanism arranged above the line guide, and a tray into which the sheets are fed in stacked relation by the sheet feeding mechanism, projecting rearwardly from the discharge of the said sheet feeding mechanism.
- 40 9. A copy holder comprising a line guide, a sheet feeding mechanism arranged above the line guide, a tray into which the sheets are fed in stacked relation by the sheet feeding mechanism, projecting rearwardly from the discharge of the said sheet feeding mechanism, and a sheet holding tray arranged below the line guide and projecting rearwardly beneath the receiving tray.
- 45 10. A copy holder comprising a line guide, a sheet feeding mechanism arranged above the line guide, a tray into which the sheets are fed in stacked relation by the sheet feeding mechanism, projecting rearwardly from the said mechanism, and a sheet holding tray arranged below the line guide and projecting rearwardly beneath the receiving tray, both of said trays declining rearwardly from their forward ends.
- 50 11. In a copy holder, the combination with a frame and sheet clamping and feeding means arranged thereon, of a sheet supporting device arranged to the rear of the frame and having a rearwardly extended surface to support the rear end of the sheet as it is fed by said clamping and feeding means.
- 55 12. In a copy holder, the combination with a frame and sheet feeding means arranged thereon, of a sheet supporting device arranged to the rear of the frame and having an extended surface projecting forwardly and upwardly to a point beneath the sheet feeding means to support the sheet and direct it to said feeding means.
- 60 13. In a copy holder, the combination with a frame and sheet feeding means arranged thereon, of a sheet supporting tray projecting to the rear of the frame below the feeding means, and a line finder arranged between the supporting tray and feeding means and adapted to cooperate with the sheet.
- 65 14. In a copy holder, the combination with a frame and sheet feeding means arranged thereon, of a pair of sheet supporting trays projecting rearwardly from the feeding mechanism, one above the other, the lower tray having its forward portion in front of the feeding plane and the upper tray having its forward portion in rear of the feeding means and also below the discharge portion thereof.
- 70 15. In a copy holder, the combination with a frame and sheet feeding means arranged thereon, of a receiving tray arranged on the discharge side of the feeding means below and in rear of said discharge, and a sheet deflector arranged above the discharge to engage the sheet discharged from the feeding means and deflect it to the sheet receiving tray.
- 75 16. In a copy holder, the combination with a frame, a shaft supported at its ends in said frame, a feed roller mounted on said shaft to turn therewith, a second shaft movable in said frame, a roller on said shaft, and means for moving said roller into and out of engagement with said feed roller on one side of said feed roller, of means for reinforcing the shaft of the feed roller between its ends on the side disposed away from the second shaft.
- 80 17. In a copy holder, the combination with a frame, a shaft supported in said frame at its ends, feed rollers mounted on said shaft,

and clamping devices movable into engagement with said feed rollers on one side of the shaft, of adjustable means for reinforcing said shaft between its supported ends on the side disposed away from the clamping means.
